UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

PRESSURE-REGULATING DEVICE.

Application filed January 10, 1925. Serial No. 1,714.

To all whom it may concern:

Be it known that I, LEWIS C. BAYLES, a citizen of the United States, and resident of Easton, county of Northampton, and 5 State of Pennsylvania, have invented a certain Pressure-Regulating Device, of which the following is a specification, accompanied by drawings.

This invention relates to compressors, but 10 more particularly to a device for regulating the flow of pressure fluid into a storage receiver, wherein it may be desirable to control the pressure to a degree more suitable for certain requirements, as for instance, inflating automobile tires, in which over-inflation frequently occurs due to excessive pressures within the receiver.

It has been found that if the compressor cylinder is opened to atmosphere after the 20 desired pressure has been attained in the receiver, the compressor may be operated more economically and more efficiently because of an additional cooling effect on the compressing element.

25 The principal object of this invention is to prevent the storage of compressed fluid within a receiver in excess of a certain predetermined pressure by controlling the admission of fluid into the receiver.

30 Other objects will appear hereinafter. In the drawings forming part of this specification,

Figure 1 is a sectional view in elevation of a compressor equipped with a pressure regulating device showing the position of the parts when the fluid passes into the storage receiver,

Figure 2 is a side view partly in section of a compressor equipped with the device 40 showing the compressing element in communication with the atmosphere, and

Figure 3 is a transverse sectional view taken through Figure 2 on the line 3-3 looking in the direction of the arrows.

45 Referring to the drawings, the invention is shown embodied in a single acting compressor unit consisting of a water-cooled cylinder A having a compression chamber B, and a reciprocating piston C. In this instance, a fluid tight crank case D, having a suitable outlet D', serves as a storage receiver for the compressed fluid and is in communication with the compressing end of the chamber B through a suitable passage E. An inlet valve F in communication with

the atmosphere is arranged within a water-cooled cylinder head G to admit air into the chamber B, while a discharge valve H controls the flow of compressed fluid from the chamber B through the passage E into the storage receiver D and is preferably arranged at the discharge end of said passage.

50 The piston C is actuated by a suitable source of power, (not shown) and is in this instance connected therewith by a piston rod J operatively connected to the cross head K, and a connecting rod L, pivoted at one end on the cross head and pivotally connected at its other end to a crank O mounted on a drive shaft P.

55 Means are provided to regulate the admission of compressed fluid into the receiver D, thus maintaining a constant predetermined pressure therein. To this end a valve Q, having a stem R' and an enlarged head Q', 70 in communication with the pressure of the fluid within the receiver D, is arranged to open a transverse port R, whereby the passage E may be connected with atmosphere. The valve head Q' is preferably provided 75 with a knife-edge seat U in the form of a removable bushing screw threaded into the end of the chamber S. A spring V disposed within the bore T is adapted to bear against the end of the valve Q to hold said 80 valve normally in a closed position.

85 In the operation of the machine, fluid is admitted by the inlet valve F into the chamber B wherein it is compressed by the piston C and passes through the passage 90 E and the discharge valve H into the storage receiver D, and continues to flow thereinto until the pressure within the receiver, operating against a face X of the valve head Q', is great enough to overcome the force 95 of the spring V, the valve Q and the head Q' will then be actuated within the bores S and T until a reduced portion Y of the extension opens the transverse passage R, thus placing the chamber B and the passage E in direct communication with the atmosphere, and since the action of compression increases the temperature of the fluid thus compressed, it is obvious that the cooling effect of atmospheric air admitted 100 into and discharged from the chamber without resistance will add to the efficiency of the machine.

105 The regulating device may be adjusted to operate at different pressures within the 110

receiver by increasing or reducing the tension of the spring V . To this end a flat cylindrical plate Z is arranged slidably in the bore T to bear against the end of the 5 spring, and in this instance is adjusted by a set screw b .

Assuming that a higher pressure of fluid is desired within the receiver D , the tension of the spring V may be increased by screwing 10 the set screw downwardly, thereby affording greater resistance against the action of the compressed fluid within the receiver, and consequently requiring a higher pressure to raise the valve Q against the 15 force of the spring.

In order to insure positive seating of the valve head Q' when the pressure within the receiver D is sufficiently reduced to again permit said head to approach the seat U , a 20 passage c is formed within the wall of the bore S , and is of suitable length to communicate at both ends with the bore S at the opposite faces of the enlarged head Q' of the valve Q , when said head rests on the 25 seat U . As the head Q' approaches the seat U and the pressure within the receiver still counterbalances the force of the spring V , air will pass through the port c to the rearward face of the enlarged head Q' of the 30 valve Q and augment the force of the spring V to return the head to the seat U . The passage c also permits the escape of air entrapped between the outer portion of the valve face X and the seat U , into the uppermost portion of the bore S and thence 35 through a vent d to atmosphere. Direct leakage of fluid from the receiver through the passage c is prevented, for the reason that when the head Q' starts to move from

the seat U , it immediately covers the innermost opening of the passage c and is designed to uncover the opening only when said valve is in its closed position.

I claim:

1. In a compressor comprising a storage 45 receiver, and a compressing cylinder having a passage communicating with said cylinder and the storage receiver, a piston to reciprocate within the cylinder, a valve actuated by fluid under pressure within the storage receiver to open communication between the cylinder and atmosphere, a spring to return the valve to its normally closed position, means to augment the force of the spring to return the valve to its closed position, and 50 an adjusting member to vary the tension of the spring for attaining different pressures within the storage receiver.

2. In a compressor comprising a storage 55 receiver, and a compressing cylinder having a passage communicating with said cylinder and the storage receiver, a piston to reciprocate within the cylinder, a valve actuated by fluid under pressure within the storage receiver to open communication between the cylinder and atmosphere, a spring to return the valve to its normally closed position and means to augment the force of the spring to return the valve to its closed position including a head for said valve, a cylinder for 60 the head provided with a passage controlled by the valve head to connect opposite ends of the cylinder whereby opposite faces of the valve head are exposed to pressure fluid from the receiver.

In testimony whereof I have signed this specification.

LEWIS C. BAYLES.
